UNITED STATES PATENT OFFICE.

WALTER N. NORWOOD, OF LOS ANGELES, CALIFORNIA.

VAPOR APPARATUS.

Application filed May 14, 1923. Serial No. 639,032.

To all whom it may concern:

Be it known that I, WALTER N. Norwood, a citizen of the United States, residing at Los Angeles, in the county of Los Angeles 5 and State of California, have invented new and useful Improvements in Vapor Apparatus, of which the following is a specification.

This invention relates to improvements 10 in means for generating vapors and gases from air, earth, wood and other substances and is an improvement upon patent numbered 986,202, granted to me March 7, 1911.

15 Like the above mentioned patent, the present invention aims to provide a simple, reliable, effective and economical apparatus whereby medical vapors or gases of various kinds may be rapidly and conveniently generated and used in the treatment and cure 20 of various internal and external disorders or diseases of the human system and for the prevention of contagious and infectious diseases.

25 It has been found however, that the time necessary to generate a sufficient amount of vapor or gas for the treatment of a patient is from one to two hours, depending upon atmospheric conditions, the average time being about one and one-half hours. The 30 amount of gas or vapor which is generated would last from one to one and one-half hours, also depending upon atmospheric conditions, so that after the treatment of a 35 patient it would require from one to two hours to produce sufficient vapor or gas for the treatment of the next patient.

It has also been found that owing to the 40 arrangement of the flue which connects the generator or furnace with the treatment cabinet, that the products of combustion, smoke and fumes would back up into the furnace through the furnace opening instead of going up the flue and to lower the door of 45 the furnace before the fire burns to its proper degree of heat, would cause the fire to smoulder and interfere with the proper generation of the gas.

The present invention has for its primary 50 object the overcoming of these objectionable features and in addition, cheapens the construction of the apparatus without in any manner detracting from its efficiency.

With the above and other objects in view, 55 the invention further includes the following

novel features and details of construction, to be hereinafter more fully described, illustrated in the accompanying drawings and pointed out in the appended claims.

In the drawings:—

Figure 1 is a side elevation of a vapor or gas generating apparatus embodying my invention.

Figure 2 is a top plan view of the same.

Figure 3 is a vertical longitudinal section 65 through the apparatus.

Figures 4, 5 and 6 are cross sectional views taken on the lines 4—4, 5—5, and 6—6 respectively of Figure 1.

Figure 7 is a front elevation of the furnace or heater.

Referring in detail to the drawings, wherein like characters of reference denote corresponding parts, by reference to Figure 2 it will be seen that in the present form of the 75 invention there are provided two furnaces, suitably spaced apart and indicated at 1 and which are designed for the vaporization and generation of gases from wood and other suitable material. The furnaces include 80 suitable internal construction for burning or otherwise subjecting the material to the action of heat for the liberation of gases or vapors therefrom. They are embedded in the earth for an appreciable depth 85 and their fronts are exposed by suitable pits 2 which are formed in the ground so as to permit of access to the furnaces. As shown the fronts of the furnaces are provided with openings for the insertion of the 90 material to be treated and the removal of the residue after treatment, as well as the inlet of air for supporting combustion. This opening is controlled by a vertically slidable door 3, whose side edges extend beyond the 95 side edges of the opening. The door 3 is suspended from a rope or cable 4 which passes over suitable pulleys 5 and has attached thereto a weight 6 which balances the weight of the door. By pulling down upon the weight, the door may be elevated and sustained in any desired position, or by raising the weight the door may be opened and will close by gravity. For the purpose of holding the door in open position, the present invention contemplates the use of a rod 10 or prop 3^a, the said rod or prop acting to hold the door at any suitable height and causing it to securely engage the front of the

11 furnace.

Extending from each furnace 1 are rearwardly projecting passages or flues 7. These passages or flues are located below the surface of the ground and have one of their ends in communication with the rear ends of the furnace 1 by means of an upwardly inclined portion 7^a, so that the vapors and gases from the furnaces will rise upward. The ends of the flues remote from the furnaces join and communicate with a common flue 7^b and extending from this last mentioned flue are upwardly extending branches 9, each of which communicates with a treatment box or cabinet 8. The passage of the vapor of gases to these cabinets is controlled by a valve 10, which is provided with a stem 11 extending upwardly through the ground to the surface, so that the valves may be readily manipulated to open and close the supply of gas or vapor to either of the cabinets. Each cabinet consists of a box-like structure open at the top and provided at one end with an upwardly extending exhaust flue 12 for the passage of the vapors under certain conditions after use, the branch 9 forming the inlet to said cabinet opening through the bottom thereof at any suitable point along its length. The cabinets are arranged within a house or suitable enclosure at a desired distance from the furnace 1.

The flues 7 extend through a primarily formed ditch and are covered with earth up to the ground level and in addition to the upwardly inclined portions of the flues, the latter preferably slightly incline at a suitable angle from their inlet to their delivery ends to facilitate the flow of vapors or gases therethrough. The flues are formed of side and top walls of porous brick or tiling and are open at the bottom, so that the vapor or gas on its flow therethrough will extract from the earthen base and through the porous walls of the flue, the moisture and medicinal properties of the salts of the earth. The flues are separated into a plurality of channels by vertical partitions or division walls 13 and the latter are interrupted or provided with communicating ports 14 at spaced intervals, so that gases or vapors flowing through the several channels will pass from one to the other and thus become thoroughly co-mingled on their travel through the flues to the cabinets.

Each of the flues 7 is provided at one or more points along its length with a medicament supply pipe or inlet 15 extending upwardly therefrom to a point above the surface of the earth and through which any desired liquid or solid medicament from which it is desired to generate a gas or vapor may co-mingle with the vapor from the furnace and may be interposed and converted into vapor by the heat of the vapor from the furnace. The pipe 15 is provided

with any suitable top or closure 16 and may also be employed for admitting air to the flue to co-mingle with the vapor when such a combination is desirable. Also communicating with each of the flues are one or more chimneys or outlets 17 for the escape of noxious gases and products of combustion initially generated in the furnace, each of which chimneys or outlets is provided with a suitable closure 18. Below each chimney the flues are deepened or extended as at 19 to provide pockets or reservoirs into which medicinal substances which are to be converted into gases or vapors to co-mingle with those of the furnace, may be introduced, thus allowing for different kinds of compositions of vapors to be generated and co-mingled according to the nature of the disease or disorder to be treated.

Beyond each chimney 17, the flue is provided with a valve or a damper 20 which has a controlling handle or stem 21 extending through the earth to the surface, whereby the valve or damper may be adjusted to regulate the speed of flow of the vapor or gas through the flue. Each valve or damper shown may also be completely closed for the purpose of preventing the noxious vapors and products of combustion initially generated by the furnace from passing through the flue to the cabinet and for causing them to discharge through the chimney and medicament inlet associated therewith, allowing all of the noxious substances to entirely discharge.

As soon as these substances discharge and the generation of an innoxious medicinal vapor begins, the outlets 15 and 17 are closed and the dampers 20 opened for the supply of the vapors or gases to the cabinets, it being apparent that the cabinets may be independently or simultaneously supplied with vapor as occasion may demand.

The treatment of patients with this form of apparatus is substantially the same as that described in my former patent. In the present form of the invention however, sufficient gas or vapor may be generated in one of the furnaces and when its proper medicinal value is reached, it may be conducted to either one or both cabinets through the manipulation of the dampers, the purpose being however, to conduct it to one cabinet for the treatment of a patient. While this treatment is being effected, vapor or gas may be generating within the other furnace and the other cabinet will thus be ready for the reception of a patient at approximately the same time the patient is ready to leave the first used cabinet. A continuous operation of the apparatus is thus possible by the alternate use of the cabinets. Further, by arranging the invention in the manner described, different kinds of vapors or gases

may be generated to treat both internal and external diseases with the use of the same cabinets, one furnace operating to produce gas or vapor best suited for internal diseases, while the other furnace may be used to produce gas or vapor best suited for external diseases, so that two classes of patients may be treated at the same place with the use of the same cabinets.

10 It is believed by many medical men, that if creosote could be administered direct into the lungs and not into the stomach, that tuberculosis could be cured. By my method of apparatus creosote is obtained in a gaseous form and breathed direct into the lungs. Passing the smoke, fumes or vapors through the ground, as per my invention or apparatus, is a method by which the medicinal substances and helping agents or gases may 15 be obtained direct from the earth and administered direct into the system through the respiratory tract to cure and prevent internal diseases. By the method or process of my invention or apparatus of passing 20 through the earth the smoke, fumes or vapors from the burning of wood, the irritating, stifling and offensive substances are eliminated and the medicinal substances in 25 the ground are drawn into the vapors.

30 When the fire in the furnace first commences to burn, it starts off making genuine natural smoke; as the heat from the fire increases the substances of the earth are drawn into the flue and begin to form vapors or 35 gases. This process continues forming more gas and less smoke, more gas and less smoke, until a certain stage of heat and generation is attained whereby the irritating, stifling and offensive properties of smoke are eliminated. Although the vapors or gases are 40 very hot when coming from the furnace, they are cool and pleasant to inhale when they reach the cabinet, by passing through the ground.

45 The invention is susceptible of various changes in its form, proportions and minor details of construction and the right is herein reserved to make such changes as properly fall within the scope of the appended 50 claims.

Having described the invention what is claimed is:—

1. A gas or vapor producing apparatus comprising a plurality of generators, a plurality of receptacles for the gas or vapor, 55 underground conducting flues connecting the generators and receptacles, said flues being porous for communication with the surrounding soil to extract the moisture and medicinal substances therefrom and means for directing the flow of gas or vapor from the generators to any of the receptacles.

2. A gas or vapor producing apparatus comprising a plurality of generators, a receptacle for each generator, underground 65 flues connecting each generator and receptacle, said flues being porous for communication with the surrounding soil to extract moisture and medicinal substances therefrom and means whereby the flow of gas or vapor 70 through the flues may be controlled to direct said gas or vapor from either of the generators to either of the receptacles.

3. A gas or vapor producing apparatus comprising a plurality of generators, a receptacle for each generator, a substantially Y-shaped underground flue having its adjacent ends connected to the generators, said flues being porous for communication with the surrounding soil and having their adjacent ends connected to the generators, branch conduits connecting the opposite end of the Y-shaped flue with each of the receptacles and means for controlling the passage 80 of gaseous vapors from the generators to the 85 receptacles.

4. A gas or vapor producing apparatus comprising a generator, a receptacle for the gas or vapor, an underground conducting flue, said flue being horizontally arranged 90 and on a plane above the generator and being porous for communication with the surrounding soil, an upwardly inclined conduit extending from the generator and communicating with one end of the flue and means 95 establishing communication between the other end of the flue and the receptacle.

In testimony whereof I affix my signature.

WALTER N. NORWOOD.
